UNITED STATES PATENT OFFICE

168,985

FOUR-IN-HAND TIE PRESS OR SIMILAR
ARTICLE

James H. Braley, Sacramento, Calif.

Application July 28, 1952, Serial No. 20,786

Term of patent 14 years

(Cl. D49—1)

To all whom it may concern:

Be it known that I, James H. Braley, a citizen of the United States, residing at Sacramento, Sacramento County, California, have invented a new, original, and ornamental Design for a Four-in-Hand Tie Press or Similar Article, of which the following is a specification, reference being had to the accompanying drawing, forming a part hereof.

Figure 1 is a top perspective view of a four-in-hand tie press showing my new design;

Figure 2 is a top plan view;

Figure 3 is a side elevational view; and

Figure 4 is an end elevational view.

I claim:

The ornamental design for a four-in-hand tie press or similar article, substantially as shown.

JAMES H. BRALEY.
